CATAMENIAL PAD HOLDING DEVICE

Emanuel R. Morando, New York, N. Y.

Application March 18, 1942, Serial No. 435,154

4 Claims. (Cl. 128—290)

This invention relates generally to women's wear or apparel and has particular reference to a sanitary catamenial appliance.

Heretofore absorbent pads or appliances of this type have been used with the aid of members which have included cords, tape or bands, fastening elements of the safety pin type, as well as particular articles of apparel, and one of the objects of this invention is the provision of a clamping device for holding pads with which members as aforesaid are not required.

Another of the present objects, is therefore, the provision of a sanitary device and pads, for use by women, which may be applied instantly, such as by a single manual movement, and which thereafter, by its own structure, may efficiently remain in the applied position, and the clamping or pad holding device sterilized as desired.

A feature of this invention, combined with high efficiency of a novel nature, is simplicity, and therefore on being first seen by a prospective user, in accordance with yet another of the objects involved, the manner in which the device is placed in its effective position, and the manner in which it remains in place, may be readily seen.

Still another object at present aimed at, is to provide a device or pad of this nature which may be effective to inspire its owner with confidence, it being appreciated that the exact time at which an absorbent pad may be required is not known beforehand. For this reason users of catamenial pads, which latter have required some considerable manipulation in order to place them in position, have been obliged to wear such pads when not really required, and at other times it has heretofore happened that, when such pads were required unexpectedly soon, and consequently not then in place, considerable embarrassment has been caused. Inconveniences such as these last mentioned may therefore be eliminated with the instant pad, which, moreover, is so small and compact as to be easy to carry at all times, at least at times approaching the probable times at which such pads may actually be required.

The device includes an absorbent pad element of the nature of former pads, but with no member such as any of those aforesaid, attached thereto or connected therewith.

Another feature of this invention, is a pad support having resilient fingers or spring strips adapted to assume different positions. In a closed position the pad is carried within the fingers, and the device, being of small bulk, is

easy to carry in any convenient place, such as in a box within a handbag or pocket-book.

One constructional yieldable material, which is suitable for said fingers, is whalebone. As well as said closed position, the resilient fingers have a substantially open position, and they may instantly, manually, be changed from the closed to the open position. In the open position the location of the pad becomes outermost. In this latter position, with the pad outermost, the spring fingers are held with the hand, that is, grasped by the fingers of the hand, and there held against outward springing action. In this way, the pad is placed directly against the vulva, in the usual place, and the spring fingers are released. Said spring fingers then suitably expand, pointing downwardly and outwardly, and holdingly engage against the thighs. On each side or thigh, one finger may be about central, with other fingers spaced from it and at the front and back thereof, as shall hereinafter appear in detail.

With the above indicated objects and advantages in view, as well as others which will hereinafter appear, this invention resides in certain novel constructions and arrangements of parts, the essential features of which are herein fully described, and illustrated in the accompanying drawing, in which:

Figure 1 is a plan view of the under side of a catamenial device including a pad;

Figure 2 is a side view of the device in closed position;

Figure 3 is a side view in which the device is open, and with the spring fingers moved together further than in normal use;

Figure 4 is a view of the device as found in use;

Figure 5 is a section on the line 5—5 of Figure 4;

Figure 6 is an enlarged cross section of a spring finger on line 6—6 of Figure 1;

Figure 7 shows a spring finger embedded in a suitable soft covering;

Figure 8 shows a spring finger with a rubber tip portion;

Figure 9 shows the spring fingers formed in one integral member;

Figure 10 shows the device and pads as placed into a box for the trade, and for carrying around.

As shown in the particular embodiment of this invention selected for illustration in said drawing, the device includes a whalebone structure having resilient or yieldable fingers or

strips 10, 11 and 12. Opposite to these fingers or also similar finger or strips 13, 14, 15.

In the present instance the fingers 10, 12 and 13, 15 are formed integrally from one piece, it being seen that they are joined at the central part 16, and the fingers 11, 14 are also formed from a single piece, having a center 17. The centers of the two pieces shown herein are joined together by an eyelet 18.

The whalebone from which the spring fingers are formed is of a depth or thickness, and width, which are suitable for the required strength, but I have found a depth of about one-sixteenth of an inch, and a width of about one-fourth of an inch to give satisfactory results. Also, when the spring fingers, such as each member 11, or 14, are about three inches in length, the assembled device functions satisfactorily, but other dimensions, as well as other materials, may be used. It follows, for example, that a stronger and more rugged assembly than that which is illustrated may be constructed, and although the drawing is of a diagrammatic nature, as in Figures 1-4, all fingers and members are suitably beveled entirely therearound, as may be seen from the sectional showing of Figure 6, at 21, 22.

An absorbent pad 20 forms part of the assembly, and this may be of usual material, and also of dimensions substantially as known in practice. The pad 20, which may have a covering of fabric, such as cheese cloth material, should however, be about an inch in depth and of certain yieldability, since it is held in position by pressure of the central part or seat 16, 17 of the supporting means. The pad may have thereon at the back central part, which engages the support 18, 17, adhesive material, so that when the latter is moistened, it may become attached to said support. The pad 20 is accordingly readily removable from the support, as such pad may be exchanged for a new one as often as found necessary. It is a feature of the whalebone, in this respect, that it retains its efficient qualities for a relatively long period of time.

If desired the resilient fingers may be expanded or of an enlarged nature terminally, at their free ends, as shown in Figure 1 to assure ease of wear. Said fingers also may be formed with bends B or waves, in order to increase their holding efficiency, as against the fleshy parts or thighs of a user.

The device is shown in Figure 1 in flat position, and in Figure 2 in certain closed or folded position. When required for use, as taken from the Figure 2 position, the fingers 10-12, 13-15 are turned into approximately the Figure 3 position, and thus held with the fingers of one hand therearound.

In this position, it is seen that the pad 20 is on the outer side. Then, merely with said hand, the pad 20 is placed directly in the required place, against the passage end, on the vulva, and when the pressure or inward urge is sufficient the fingers 10-12, 13-15 are released, whereupon to lightly engage the thigh parts 28, 29 thereat, as illustrated in Figures 3 and 4.

The central members, as 11, 14 are then central, or projecting directly downwardly, the medial and outwardly inclined parts of the fingers 30, 31, 32, 33 are also disposed respectively forwardly and backwardly, and the ends or terminals of said fingers, as 12, 10, are likewise directed substantially directly downwardly.

As in Figure 5, it is seen that the central members, the member 11 being shown, may not be

exactly at the nearest portions of the thighs, but rather forwardly thereof. This tends to incline the front end 34 of the pad upwardly, and the other end 35 downwardly, which is the practical and engaging position for said pad. In Figure 5, for example, the finger end 10, and the corresponding finger on the opposite side, are in position below and at the buttocks. This positioning and finger engagement tend to hold the pad correctly in the engaged position during bodily and leg movement.

The outer strip members, as 10, 12, have certain bends therein, this being where the end portions are continuous with the outwardly inclined portions 30, 31 and the free ends of the strips, from said bends, as shown, as substantially parallel. At said bends, also, the material of the strips may be slightly turned, so that the planes of the outer end portions (see the members 10, 12, Figure 5) are out of parallelism with the plane of the central end portions. This turning of the outer terminal portions 10, 12, 13, 15, causes them to fit flatwise against the thighs, at the arcuate transverse curve lines thereof.

The illustrations selected for disclosure in the instant invention are representative of preferred positions, and others may be used in practice, it being understood, for example, that, in the positioning of Figure 4, the spring fingers may be closed more closely together, or the reverse, depending upon the distance apart of the upper portions of the thighs. This distance may be more or less, in different individuals, and in different devices.

The showing of Figure 9 is identical with the other embodiments, except that all six spring members extend from one central piece 41 or support.

In Figure 7 the spring fingers are embedded in any suitable covering 45, which may or may not be integrally formed with the pads.

In Figure 8 the springs are shown covered with a rubber tip 46, that may be attached and removed therefrom.

In Figure 10, my device with pads, is shown arranged in a sanitary covering 47 within a suitable container or box 48.

Variations other than those illustrated may be resorted to within the scope of the invention and parts of the improvements may be used without others.

Having thus described my invention, what I claim as new and desire to secure by Letters Patent of the United States of America, is as follows:

1. A catamenial pad holding device of the class described comprising a pad support having on opposite sides thereof two groups of spring fingers, each group including a central member having a base part and a terminal portion, front and back members on opposite sides of the central member and having respectively forwardly and outwardly inclined and backwardly and outwardly inclined base parts, and free portions extending from said parts and having rounded and expanded terminals thereon.

2. As an article of manufacture, a catamenial pad holding device having closed and open positions including a central supporting portion having an absorbent pad thereon, and resilient fingers extending from said portion and having, when the device is closed, fingers disposed around the pad in protecting relation therewith, said fingers having, when the device is open, substantially opposite positions, the pad being on the

outermost side of the support in the open position.

3. A catamenial pad holding device of the class described comprising a supporting portion having on the top thereof an absorbent pad for engaging the vulva, two opposed lateral groups of resilient and yieldable fingers extending from said support, each group including a central base part for engaging the upper parts of the thighs, front and back base parts on opposite sides of the cen- 10

tral parts and spaced therefrom, said front and back parts adapted to follow the convex form of the thighs, and downwardly disposed parts extending from the base parts and also adapted to engage the thighs.

4. A catamenial pad holding device according to claim 3, in which said base parts are formed with wavy edges.

EMANUEL R. MORANDO.
